CLAIM

The ornamental design for a caulking tube nozzle, as shown and described.

DESCRIPTION

FIG. 1 is a left side view of the caulking tube nozzle.

FIG. 2 is a right side view thereof.

FIG. 3 is a top view thereof.

FIG. 4 is a bottom view thereof.

FIG. 5 is a front view thereof; and,

FIG. 6 is a top perspective view thereof.

The broken lines are for illustrative purposes only and form no part of the claimed design.
